UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

TYPOGRAPHIC CASTING-MACHINE.

1,300,271.

Specification of Letters Patent. Patented Apr. 15, 1919.

Application filed October 19, 1918. Serial No. 258,861.

To all whom it may concern:

Be it known that I, MAURITZ C. INDAHL, a citizen of the United States, and a resident of Philadelphia, county of Philadelphia, 5 State of Pennsylvania, have invented certain new and useful Improvements in Typographic Casting-Machines; and I do hereby declare the following to be a clear, full, and exact description of the same, reference being had to the accompanying drawings, and to the characters of reference marked thereon.

This invention relates to type casting machines, particularly of the class manufactured by Lanston Monotype Machine Company and represented for example, by United States Letters Patent No. 625998 dated May 30, 1899. Such machines, generally speaking, comprise a mold over which a matrix holder may be accurately centered and lowered to seat a matrix therein upon the mold above the mold cavity thereof, mechanism for injecting molten type metal into the mold cavity and against the matrix, mold 20 operating mechanism for sizing the type and ejecting it from the mold and further mechanism for conveying the ejected type to a galley forming a part of the machine, all of these various elements being operated in 25 timed relation. In certain of these machines a plurality of matrices is contained in the holder and a selected matrix is capable of being positioned over the mold by the action of positioning devices which cause movements of the holder in its own plane. The 30 movements toward and away from the mold are normal to this plane and are effected by a lever mechanism.

In operating machines of this kind it is 35 often necessary to remove the matrix holder or case and insert one holding another matrix or arrangement of matrices. In machines of this kind the matrix case has a hook extension which engages with a complementary shaped yoke plate or cross slide this connection being such that in the normal operation of the machine which includes the raising and lowering of the matrix case, there is no breaking of this connection. A 45 buffer is provided to prevent this breaking by preventing overthrow caused by vibration or jarring; but it is removable so that when removed the case can be raised to what may be termed an abnormal position in which it is disconnected from the cross slide 55

and may be withdrawn from the machine.

It is the object of the present invention to produce a device by the operation of which the disconnecting when desired of the matrix case from the cross slide and its removal 60 from the machine may be conveniently and easily done in an insignificant amount of time. The mechanism of the invention comprises a lifting lever and a buffer removing lever, both levers being arranged in such a 65 manner that the buffer removing lever operates preliminarily to the lifting lever to move out of normal position the mechanical buffer, following which the lifting lever is operated to raise the matrix case to the abnormal position mentioned.

The construction of the device of the invention will be more particularly set forth in connection with the following description of the embodiment of the invention shown in 75 accompanying drawings, in which—

Figure 1 is a plan view of a portion of the above mentioned typecasting machine showing the matrix case, the bridge and the mechanism of the invention associated therewith. 80

Fig. 2 is a side elevation of the mechanism shown in Fig. 1, the parts being in normal position.

Fig. 3 is an elevation of the matrix case and the cross slide.

Fig. 4 is a side elevation similar to that of Fig. 2, but showing the parts in different positions, and

Fig. 5 is a perspective view of the lever mechanism of the invention and the buffer plate.

It is not necessary to describe in detail the casting machine to which the invention has been shown applied, but it is sufficient to point out a few of the well known elements 95 of such machine which are shown in the various figures, particularly Fig. 1, for example, the bridge 1, the centering pin 2, the matrix case 3 containing the matrices 4, the cross slide 5, the draw rod 5', the centering 100 pin spring 6, the centering pin lever 7, the matrix case carrier supporting frame 8, the

carrier 9 and its draw rod 9' and the mold 10. As is well known to those skilled in the art, the centering of the matrix above the mold is accomplished by the movement of the matrix case in its carrier 9 in one direction and of the carrier in its supporting frame 8 in a direction at right angles to said first mentioned direction. Vertical movement of the matrix case to accomplish the seating and unseating of the matrix on the top of the mold is accomplished by the lever 7 operating through the link 12, lever 13 and stay 14, the latter secured to the bridge 1. The lever 13 acts at its central portion through a rod and spring 11 upon a cross bar 15 secured at its ends to the vertical rods 16 extending through the bridge and secured at their lower ends below the bridge to the frame 8. Between the bridge 1 or its depending fixed projections 1' and the frame 8 is a buffer 17, clearly shown in Fig. 5 of the drawings and usually made of fiber. This buffer is in the form of a plate pivoted centrally to the bearing 2' for the centering pin and rotatable on such pivot so as to remove its ends from between the bridge 1 and the frame 8. The portions of the buffer which enter between these elements are formed by cutting away opposite sides of the plate to form notches fitting around the standards 16, so that the buffer adjacent these notches will surround a portion of the circumferences of these standards. A spring 18 secured at one end to a projecting portion 19 of the bridge 1 and at its other end to one end of the buffer 17 maintains the buffer in normal position in which it lies between the bridge 1 and the frame 8 so as to prevent undue upward movement or overthrow of the frame 8, the carrier 9 and the matrix case 3. This is the buffer position shown in Fig. 2 and in full lines in Fig. 1.

Secured to the upper part of the bridge in proximity to one of the standards 16 is an upwardly extending casting 20 which forms a bearing for the vertical spindle 21. Screw retained bearing caps 22 complete the bearing and hold the spindle 21 in position. The spindle is provided with an annular flange 23 fitting above the upper bearing so as to prevent the spindle from downward movement in its bearing. Above the annular collar 23 of the spindle is a lateral extension 24 to which is pivoted by means of the bolt 25', the lever 25 the power end of which is indicated by the character 26. The lower end of the spindle 21 is provided with a buffer removing lever 27 which extends radially from the spindle and downwardly so as to be in position to engage with the buffer 17 when the spindle is rotated. The casting 20 has in the neighborhood of the upper bearing a lateral extension 28 having an upward flange cut away centrally so as to form upwardly extending lateral stops 29

and 30, between which the lever 25 at all times extends. The lower portion of the notch between the upstanding stops 29 and 30 is formed with a cam surface 31 for co-operation with the underneath edge of the lever 25 so that in moving the lever laterally from its normal position in contact with the stop 29 as shown in full lines in Fig. 1 to its position in contact with the stop 30 as shown in dotted lines in Fig. 2, the turning being accomplished on the vertical pivot formed by the spindle 21, the cam 31 operates to raise the lever so as to accordingly depress the power end 26 of the same and cause it to enter below the cross bar 15, the last motion of the lever being on the horizontal pivot formed by the bolt 25'. The cam 31 however, terminates before the stop 30 is reached, so that after the handle 25 has been raised to its greatest extent by the cam 31 and has passed beyond the latter, the handle may be depressed so as to enter the notch 32 between the cam 31 and the stop 30. The depressing of the handle end of the lever will of course raise the power end 26 thereof and with it the cross bar 15. The latter will raise with it the spindles 16, the frame 8, the carrier 9 and the matrix case 3.

The construction, as has been seen, is such that the operator may move the handle 25 laterally and downwardly in practically a single quick motion which moreover, is wholly controlled by the stops 29 and 30, the cam 31 and the notch 32.

The lateral swing of the lever 25 causes the lever 27 also to swing laterally from the full line position shown in Fig. 1 to the dotted line position shown in the same figure, the end of such lever 27 operating against the buffer 17 so as to rotate it against the spring pressure 18 from full line position to dotted line position of Fig. 1. In Fig. 2 the lever 25 is shown in normal position against the stop 28. In Fig. 4 it is shown in dotted lines in rotated position against the stop 29 but not depressed. In this figure moreover, the lever 27 has moved the buffer 17 away from its normal position and the matrix case has been abnormally raised to correspond with the full line depressed position of the lever 25. The matrix carrier frame 8 in this abnormally raised position abuts (as shown) against the fixed extension 1' of the bridge 1. In all of the views the center pin lever 7 is in its uppermost position. Fig. 3 illustrates the cross slide 5 and its connection with the matrix case 3, the latter being shown in full lines in hooked position with respect to the block and in dotted lines in the abnormally elevated position to which it is raised by the proper manipulation of the lever 25 and the mechanism associated with it. It will be seen from this dotted position in Fig. 3 that the matrix case 3 is

unlocked from the cross slide 5 and can be readily slid in its carrier 9 away from the cross slide and thus be withdrawn from the machine. In assembling the matrix case 5 and causing it to be locked to the machine by effecting its connection with the cross block it is merely necessary to push it into the carrier 9 when the latter is in abnormally elevated position. When the end of 10 the matrix case strikes against the plate 5' which is slightly higher than the hooked portion 5^a of the cross slide 5, the lowering of the case will accomplish its connection with the cross slide, as will readily be understood.

In the operation of the device of the present invention the centering pin lever 7 is brought to its uppermost position as shown in Fig. 2, in which the centering pin 2 is free 20 from the matrices 4 in the matrix case 3 and the carrying frame 8 is elevated into close proximity to the fiber buffer 17. The operator now grasps the handle of lever 25 preferably with the left hand, and moves it 25 laterally away from its normal position against the stop 28, thus rotating the spindle 21 and causing the lever 27 to remove the fiber buffer 17 from its normal position between the carrying frame 8 and the extensions 1' of the bridge. This lateral movement also causes, due to the cam 31 or due to 30 the raising of the handle by the operator as he moves it laterally, a depression of the power end 26 of the lever and its entering 35 under the cross bar 15. With the buffer removed from normal position and the power end of the lever 26 in contact with the lower side of the cross bar 15, the operator then depresses the handle of lever 25 so that it enters into the notch 32, thus raising the power 40 end 26, the cross bar 15, the spindles 16, the carrying frame 8, the carrier 9 and the matrix case 3, the latter being raised to a position which is abnormal because the frame 8 45 now contacts with the underneath side of the extension 1', as shown in Fig. 4 of the drawings. With the right hand the operator may now readily grasp the matrix case so as to slide said case from its carrier. He 50 may also while retaining the parts in the position described, seize another matrix case and slide it into position, the forward end passing over hook 5^a and striking the plate 5' of the cross slide 5 as a stop. The release 55 of lever 25 will allow the matrix case 3 to drop into hooked connection with the cross slide 5, this action causing the raising of the lever 25 and its release from the notch 32.

Moreover, the lever 25 will be returned 60 laterally to its normal position through the action of the spring 18 which in returning the buffer to normal position will cause the latter to act upon the lever 26 and turn it and the spindle 21 and lever 25 until the latter strikes against its normal stop 29. It

will be seen therefore that the various mechanisms are automatically returned to normal positions.

I claim:

1. A type casting machine provided with 70 a matrix case and means for moving it, and in combination therewith, a buffer for preventing abnormal movement of the case and means for removing the buffer to inoperative position and moving the case to abnormal 75 position.

2. A type casting machine embodying a 80 matrix case, a mold, means for moving the case toward and away from the mold, a buffer for preventing in the movement of the case away from the mold, an overthrow thereof to an abnormal position, and in combination therewith, a lever device for rendering the buffer inoperative and moving the case to abnormal position. 85

3. A type casting machine embodying a 90 matrix case, a carrier therefor in which the case is slidable and means for moving the carrier, and in combination therewith, a buffer for preventing abnormal movement of the carrier and means for removing the buffer to inoperative position and moving the carrier to abnormal position to permit the withdrawal of the case from said carrier.

4. A type casting machine embodying a 95 matrix case, a carrier therefor, means for locking the case to the machine while permitting it to slide in the carrier and means for moving the carrier, and in combination therewith, a buffer for preventing abnormal 100 movement of the carrier and means for removing the buffer to inoperative position and moving the carrier to abnormal position in which the case is unlocked and may be withdrawn from the machine. 105

5. A type casting machine embodying a 110 matrix case, means for locking it to the machine, means for moving the case, and in combination therewith, a buffer for preventing abnormal movement of the case to a position in which it is unlocked from the machine and means for removing the buffer to inoperative position and moving the case to said abnormal unlocked position.

6. A type casting machine embodying the 115 following instrumentalities, to-wit: a matrix case, a mold, means connected with the case for positioning a matrix therein over the mold, means for moving the matrix toward and away from the mold, a buffer for preventing abnormal movement of the matrix away from the mold to a position in which the matrix case is unconnected with the positioning means, and means for moving the buffer to inoperative position and moving the case to abnormal, unconnected position whereby the case may be removed from the machine. 120

7. An attachment for type casting machines comprising a matrix case, a support 125

therefor in which the case is adapted to move in its own plane and in a direction normal thereto, a buffer to prevent movement to an abnormal position in the last-named direction and a manually operable lever mechanism for moving the buffer to inoperative position and moving the case to said abnormal position.

8. An attachment for typecasting ma-

chines comprising a buffer removing lever 10 pivoted to the machine, and a matrix case lifting lever pivoted to said first mentioned lever, said levers operating in planes normal to each other and said first mentioned lever adapted to operate preliminarily to said lifting lever.

MAURITZ C. INDAHL.
